UNITED STATES PATENT OFFICE

2,453,161

BUTT CONTACT MOUNTING FOR ROTARY SWITCHES

Harold E. Schleicher, West Hartford, Conn., assignor to The Arrow-Hart & Hegeman Electric Co., Hartford, Conn., a corporation of Connecticut

Original application November 26, 1943, Serial No. 511,855. Divided and this application July 28, 1945, Serial No. 607,555

16 Claims. (Cl. 200—6)

1

This application is a division of my copending application Serial No. 511,855 filed November 26, 1943, entitled "Rotary magnetic switch."

This invention relates to circuit breakers whose contacts are operated to open and closed positions by rotary motion. It is useful generally in circuit making and breaking devices but is particularly adapted for use in an electromagnetically operated circuit making and breaking device.

Modern battle conditions require electrical control apparatus to withstand high impact shocks, the shock test requirements having recently been increased more than tenfold. Attempts heretofore to meet the test requirements involved the addition of counterweights, inertia hammers, special brush-type contacts, etc., to existing conventional commercial structures. These have proved unsatisfactory under the new requirements. A new approach to the problem was needed to produce a scientifically designed device in which the movable parts would be dynamically and statically balanced.

It is an object of the present invention to provide contact structure for an electromagnetically-operated circuit maker and breaker, said contact structure being constructed—on like principles to the operating mechanism of the breaker—to withstand high impact tests by providing for dynamic and static balance of its moving parts. A related object is to provide an improved construction and mounting of butt type contact structure for use in rotary electric switches and circuit breakers generally, but particularly useful in balanced electromagnetically-operated rotary switches.

Another object is to provide a butt type bridging contact structure for rotary switches which will maintain a firm and consistent pressure against the fixed contacts, and, concomitantly to provide a mounting for said bridging contact which, despite possible manufacturing inaccuracies, will enable the bridging contact to adjust itself to the fixed contacts for firm engagement therewith.

Another object is to provide a bridging contact of the foregoing self-adjusting type, of which several may be mounted on a common shaft for movement together to engage different sets of fixed contacts whose positions may vary due to manufacturing tolerances and inaccuracies, and all of which will properly engage their complementary fixed contacts.

Another object is to provide for maintaining the circuit closed in case of momentary disengagement of the butt contact elements. A related

2

object is to provide means to cause the circuit maintaining contacts to come into engagement after the butt contacts became engaged and to disengage before the butt contacts separated.

5 Another object is to provide for a resilient mounting and engagement of the contacts in a butt type contact structure for use under the aforesaid conditions and to provide for positive movement to cause contact engagement and disengagement.

Other objects and advantages will become apparent as the invention is described in connection with the drawings.

In the drawings—

15 Fig. 1 is a perspective view of a device embodying the invention;

Fig. 2 is a perspective view of one section of the device illustrated in Fig. 1 and embodying the novel type butt contact structure and mounting 20 forming the invention;

Fig. 3 is an elevational view of the section illustrated in Fig. 2;

Fig. 4 is an exploded perspective view of the contact structure of Figs. 2, 3 and 5;

25 Fig. 5 is a fragmentary detail of the contact mounting of Figs. 2 and 3;

Fig. 6 is a section view taken along lines 6—6 of Fig. 5.

Referring to the drawings, main switch contacts and electromagnetic operating mechanism therefor are housed within a cylindrical sectional casing, built up from molded insulating discs 60, 102, 108, 112, 122, 130 and a metal shell 34, all of which are ultimately supported from a base plate

30 by means of the mounting plates 31 and 32 bolted on said base plate and extending at right angles to the face thereof. The immediate support for the casing sections is four spaced parallel rods 36, 37, 38, 39 running between and supported

35 by mounting plates 31, 32, and running through holes formed in each of the parts that make up the casing.

Although the casing comprises a number of sections or units, A, B, C, D, E and F as disclosed in my copending application Serial No. 511,855, the present invention is only concerned with the contact structure and mounting therefor in the sections C, D and E, which may be identical or substantially so.

45 One suitable type of operating means is the electromagnet disclosed in my copending application Serial No. 511,855, but the invention is not limited to use with such operating means. If such operating means is used, the movable contact structure, forming the subject of the

present invention, and the movable portion of the magnetic operating mechanism may be mounted on the main shaft 40 whose axis is the main axis of the device, and may have its ends journaled in and supported by the mounting plates 31 and 32. An insulating sleeve 41 is provided to insulate the shaft from all the parts it carries.

One or more of contactor sections C, D or E may be used. Since they may be identical or substantially so, description of one will suffice. The housing or base for each section may comprise a spacing disc 108 and a mounting disc 102, molded from insulating material and suitably recessed and apertured for the fixed contacts, the movable contact structure and the main shaft.

The fixed contact members may be identical in structure and comprise stamped sheet metal pieces 100 of irregular shape, as indicated in Fig. 2, mounted upon the mounting disc 102 by means of screw bolts. The members 100 have a flat central portion lying in a radial recess adjacent the periphery of the disc 102. A portion 100a of the members 100 extends radially inward into a circular recess molded into the face of the disc, within which recess the movable contact member 104 may oscillate. Welded transversely onto one edge of the inwardly-extending portions of the members 100 are rectangular contact blocks 100c of good contact material, such as silver, positioned so as to be engaged and disengaged by similar contact blocks 104c on the end of the arms 104b of the movable contact. The fixed members 100 may have an outwardly-extending terminal portion 100b which may be twisted at right angles to the central portion of the members 100.

The rotatable contact member 104 comprises a stamped sheet metal member 104a having a large central portion with a pair of counterbalancing arms 104b extending in diametrically opposite directions. To the ends of the arms 104b the contact tips 104c are permanently affixed.

For the purpose of maintaining the circuit in case of momentary disengagement of contact blocks 104c and 100c, dual supplementary contact members 106 stamped from sheet metal and lying against opposite faces of the central member 104a may be provided. Arcuate fingers 106a conforming substantially to the curvature of a radius about the axis of the movable contact may be provided on opposite sides of the main central portion in diametrically opposite positions so as to engage and disengage the inwardly-extending end 100a of the fixed contact members 100.

In order that these circuit maintaining supplementary contacts 106 shall engage their stationary counterparts after the butt-contact tips 104c engage the stationary contact blocks 100c and disengage before the contacts 104c separate from contacts 100c, the center 104a of the contact member 104 is provided with four equally-spaced, concentrically-placed, arcuate key hole slots 104s, through each of which passes one of four pins 106p that join the pair of supplementary contacts 106 by means of peened-over ends of said pins. The enlargement of the ends of the slots 104s around the pins 106p provides limited relative motion between the pins and the contact 104 to take care of manufacturing inaccuracies and to insure proper contact engagement. Lying in said slots 104s and pressing at one end against one end of the slot and at the other end against the pins 106p are small coiled compression springs 107, the springs being held in said slots by the adjacently-lying surfaces of the mid-portion of the contact

members 106. The supplementary contacts 106 and the main contacts 104 are so dimensioned that, in the disengaged or open-circuit condition, the angular distance between supplementary contacts 100a and 106a is greater than the angular distance between the butt contacts 100c and 104c. Thus the butt contacts will engage first.

Against the outside surfaces of the supplementary contact members 106 metal anchor members 109 or driving discs 109 are placed; and all of these parts are then secured together to form a permanent dynamically and statically balanced unit. A square aperture is formed in each of the parts (except the member 104a which has a large circular aperture) for the reception of the main shaft 40 of the device, so that the movable contact unit will move with the main shaft as it oscillates. By reason of the large circular aperture in member 104a through which the shaft passes freely, the member 104a turns with the shaft only insofar as connections of the member 104a through the pins 106p and spring 107 to the members 106 and 109 compel. There is thus provided a resilient lost-motion connection between the member 104a, its associated parts and the main shaft, which provides for self-adjustment of the member 104a to the fixed contacts.

Since the supplementary contacts 106 turn with the shaft 40 by reason of the non-circular connection with the shaft 40, the supplementary contacts will be positively moved to disengage the fixed contact members and will do so while the butt contacts 104c are still maintained in engagement with contacts 100c by the action of the springs 107. Since the butt contacts 104c will engage first and disengage last, the supplementary contacts will normally only be called on to maintain the circuit in case of any tendency of the butt contacts to separate. The described structure, thus, maintains continuously the closed-circuit relation of the fixed and movable contact structures, considered as a whole, by reason of the engagement of contacts 106a and 100a, so long as the shaft 40 remains unmoved, even though vibration or other causes might tend momentarily to separate the butt contacts 104c, 100c.

When the spacing disc 108 and the mounting disc 102 are placed face to face with their recesses adjacent, the movable current carrying parts are enclosed and are insulated from the parts within the sections B and D.

From the foregoing it will be understood that the movable contact structure which I have invented can adjust itself to irregularities in the location and form of the fixed contacts due to manufacturing variations and inaccuracies; and when the contacts are engaged the contact pressure will be constant and firm. Also the circuit will be maintained in spite of possible momentary separation of the butt contacts due to shock or vibration; but the danger of such momentary separation is minimized by the contacts form, as is also the amount of energy required to operate and maintain the contacts in engagement.

Modifications within the scope of my invention will occur to those skilled in the art. Therefore I do not limit the invention to the embodiment disclosed.

70 I claim:

1. In a rotary switch, a rotary shaft, a contact unit mounted thereon comprising a rigid contact member having a centrally apertured portion and a contact carrying arm extending radially, said shaft extending freely through said central aper-

ture and having limited rotary motion relative to said rigid member, an anchor member slidably mounted on said shaft but always turning therewith, spring means acting on said rigid contact member and on said anchor member and biasing said contact member but permitting it limited movement relative to said anchor member, and fixed contact means engageable by said movable contact member.

2. In a rotary switch, a rotary shaft, a contact unit mounted thereon comprising a rigid contact member having a centrally apertured portion and a contact carrying arm extending radially, said shaft extending freely through said central aperture and having limited rotary motion relative to said rigid member, an anchor member slidably mounted on said shaft but always turning therewith, and means loosely holding said rigid contact member and anchor member together, spring means acting on said rigid contact member and on said anchor member and biasing said contact member but permitting it limited movement relative to said anchor member, and fixed contact means engageable by said movable contact member.

3. In a rotary switch, a rotary shaft, a contact unit mounted thereon comprising a rigid contact member having a centrally apertured portion and a contact carrying arm extending radially, said shaft extending freely through said central aperture and having limited rotary motion relative to said rigid member, a resilient contact member beside said rigid contact member slidably mounted on said shaft but always turning therewith, spring means biasing said rigid contact member and said resilient contact member but permitting relative movement between them, and fixed contact means engageable by said movable contact member.

4. In a rotary switch, a rotary shaft, a contact unit mounted thereon comprising rigid contact member having a centrally apertured portion and a contact carrying arm extending radially, said shaft extending freely through said central aperture and having limited rotary motion relative to said rigid member, a resilient contact member beside said rigid contact member slidably mounted on said shaft but always turning therewith, means holding said rigid and resilient contact members together, spring means biasing said rigid contact member and said resilient contact member but permitting relative movement between them, and fixed contact means engageable by said movable contact member.

5. In a rotary switch, a rotary shaft, a contact unit mounted thereon comprising a bridging butt-type contact member having a centrally apertured portion through which said shaft extends freely and from which contact carrying arms extend radially, said shaft having limited rotary motion relative to said bridging member, an anchor member slidably mounted on said shaft but always turning therewith, spring means acting on said bridging member and on said anchor member, and biasing said bridging member but permitting it limited movement relative to said anchor member, and fixed contact means engageable by said movable contact member.

6. In a rotary switch, a rotary shaft, a contact unit mounted thereon comprising a bridging butt-type contact member having a centrally apertured portion through which said shaft extends freely and from which contact carrying arms extend radially, said shaft having limited rotary motion relative to said bridging member, said bridging member being recessed for the reception

of spring means, anchor members on opposite sides of said bridging member slidably mounted on said shaft but always turning therewith, spring means retained in the recesses of said bridging member by said anchor members and acting on both said members but permitting limited movement relative to said anchor member, and fixed contact means engageable by said bridging contact members.

7. In a rotary switch, a rotary shaft, a contact unit mounted thereon comprising a bridging butt-type contact member having a centrally apertured portion through which said shaft extends freely and from which contact carrying arms extend radially, said shaft having limited rotary motion relative to said bridging member, resilient contact means lying beside said bridging member and slidably mounted on the shaft but always turning therewith, spring means exerting a biasing effect on said bridging member and said resilient contact means and permitting limited relative movement of said members, and fixed contact means engageable by said bridging contact member.

8. In a rotary switch, a rotary shaft, a contact unit mounted thereon comprising a bridging butt-type contact member having a centrally apertured portion through which said shaft extends freely and from which contact carrying arms extend radially, said shaft having limited rotary motion relative to said bridging member, resilient contact means lying beside said bridging member and slidably mounted on the shaft but always turning therewith, spring means exerting a biasing effect on said bridging member and said resilient contact means and permitting limited relative movement of said members, an anchor means, and means holding said resilient contact means and said bridging member and anchor means together as a unit.

9. In a rotary switch, a rotary shaft, a contact unit mounted thereon comprising a bridging butt-type contact member having a centrally apertured portion through which said shaft extends freely and from which contact carrying arms extend radially, said shaft having limited rotary motion relative to said bridging member, an anchor member slidably mounted on said shaft but always turning therewith, spring means acting on said bridging member and on said anchor member, and biasing said bridging member but permitting it limited movement relative to said anchor member, and fixed contact means engageable by said movable contact member, each of the parts which comprise said unit being so constructed and arranged as to be statically and dynamically balanced and forming in combination with the other parts thereof a dynamically and statically balanced unit.

10. In a rotary switch, a rotary shaft, a contact unit mounted thereon comprising a bridging butt-type contact member having a centrally apertured portion through which said shaft extends freely and from which contact carrying arms extend radially, said shaft having limited rotary motion relative to said bridging member, said bridging member being recessed for the reception of spring means, anchor members on opposite sides of said bridging member slidably mounted on said shaft but always turning therewith, spring means retained in the recesses of said bridging member by said anchor members and acting on both said members but permitting limited movement relative to said anchor member, and fixed contact means engageable by said

bridging contact members, each of the parts which comprise said unit being so constructed and arranged as to be statically and dynamically balanced and forming in combination with the other parts thereof a dynamically and statically balanced unit.

11. In a rotary switch, a rotary shaft, a contact unit mounted thereon comprising a bridging butt-type contact member having a centrally apertured portion through which said shaft extends freely and from which contact carrying arms extend radially, said shaft having limited rotary motion relative to said bridging member, resilient contact means lying beside said bridging member and slidably mounted on the shaft but always turning therewith, spring means exerting a biasing effect on said bridging member and said resilient contact means and permitting limited relative movement of said members, and fixed contact means engageable by said bridging contact member, each of the parts which comprise said unit being so constructed and arranged as to be statically and dynamically balanced and forming in combination with the other parts thereof a dynamically and statically balanced unit.

12. In a rotary switch, a rotary shaft, a contact unit mounted thereon comprising a bridging butt-type contact member having a centrally apertured portion through which said shaft extends freely and from which contact carrying arms extend radially, said shaft having limited rotary motion relative to said bridging member, resilient contact means lying beside said bridging member and slidably mounted on the shaft but always turning therewith, spring means exerting a biasing effect on said bridging member and said resilient contact means and permitting limited relative movement of said members, an anchor means, and means holding said resilient contact means and said bridging member and anchor means together as a unit, each of the parts which comprise said unit being so constructed and arranged as to be statically and dynamically balanced and forming in combination with the other parts thereof a dynamically and statically balanced unit.

13. In a rotary switch, a rotary shaft, a contact unit mounted thereon comprising a bridging butt-type contact member having a centrally apertured portion through which said shaft extends freely and from which contact carrying arms extend radially, said shaft having limited rotary motion relative to said bridging member, an anchor member slidably mounted on said shaft but always turning therewith, spring means acting on said bridging member and on said anchor member, and biasing said bridging member but permitting its limited movement relative to said anchor member, and fixed contact means engageable by said movable contact member, the parts of said unit being constructed and arranged to form, in combination, a statically and dynamically balanced unit.

14. In a rotary switch, a rotary shaft, a contact

unit mounted thereon comprising a bridging butt-type contact member having a centrally apertured portion through which said shaft extends freely and from which contact carrying arms extend radially, resilient contact means lying beside said bridging member and slidably mounted on the shaft and turning therewith, spring means exerting a biasing effect on said bridging member and said resilient contact means and permitting limited relative movement of said members, and fixed contact means engageable by said bridging contact member, the angular distance between said resilient contact means and the fixed contact means complementary thereto being greater than the angular distance between the bridging contact member and its complementary fixed contact means, to cause said bridging contact member to close first and open last.

15. In a rotary switch, a rotary shaft, a contact unit mounted thereon comprising a bridging butt-type contact member having a centrally apertured portion through which said shaft extends freely and from which contact carrying arms extend radially, resilient contact means lying beside said bridging member and slidably mounted on the shaft and turning therewith, spring means exerting a biasing effect on said bridging member and said resilient contact means and permitting limited relative movement of said members, 10 and fixed contact means engageable by said bridging contact member, the angular distance between said resilient contact means and the fixed contact means complementary thereto being greater than the angular distance between the bridging contact member and its complementary fixed contact means, to cause said bridging contact member to close first and open last.

16. In an electric switch, a rotary shaft, a contact unit mounted thereon comprising a bridging butt-type contact member having a centrally apertured portion through which said shaft loosely passes, anchor members slidably mounted on said shaft and turning with the shaft, said central portion having a plurality of arcuate recesses with enlarged end portions, pins passing through said enlarged portions and holding said anchor members and bridging member together, said pins having limited motion with said enlarged end portions to permit self-adjustment of said bridging contact member, spring means in said recesses acting on said pins and affording contact pressure in switch-closed condition, and fixed butt contact means engageable by said bridging contact member.
